UNITED STATES PATENT OFFICE

144,880

DESIGN FOR A FONT OF PRINTING TYPE

Luther J. Wiesner, New York, N. Y.

Application November 15, 1945, Serial No. 123,774

Term of patent 14 years

(Cl. D64—12)

To all whom it may concern:

Be it known that I, Luther J. Wiesner, a citizen of no country, and residing at New York, county of New York, State of New York, have invented a new, original, and ornamental Design for a Font of Printing Type, of which the following is a specification, reference being had to the accompanying drawing, forming part thereof, on which are disclosed face views of the font of printing type showing my new design.

I claim:

The ornamental design for a font of printing type, substantially as shown.

LUTHER J. WIESNER.
